UNITED STATES PATENT OFFICE.

ROBERT F. DARLING, OF SENECA FALLS, NEW YORK.

SAW-CLAMPING DEVICE.

SPECIFICATION forming part of Letters Patent No. 396,145, dated January 15, 1889.

Application filed July 9, 1888. Serial No. 279,394. (No model.)

To all whom it may concern:

Be it known that I, ROBERT F. DARLING, a citizen of the United States, and a resident of Seneca Falls, in the county of Seneca and State of New York, have invented certain new and useful Improvements in Saw Vises or Clamps, of which the following is a specification.

My invention relates to improvements in vises or clamps of the class usually employed for holding saws while the teeth are being sharpened. These vises have heretofore consisted of an inner or bench jaw provided with means for adapting the vise to be applied to a bench, table, or other fixed part with facility and of an outer movable or yielding jaw.

My principal purpose is to provide improved means for setting or clamping and freeing the jaws, so that the saw may be firmly clamped for being filed and easily released, either for changing the position of the saw or for removing it after it has been sharpened, and these results I aim to accomplish in a simple and inexpensive manner.

I have set forth the distinctive features of my invention in the claims hereunto appended; but to enable others skilled in the art more fully to understand the same I will now proceed to describe my improvements with greater particularity, reference being had in so doing to the accompanying drawings, in which—

Figure 1 is a front or side view of a saw-vise embodying my improvements. Fig. 2 is an end view of the same; Fig. 3, a like representation showing some modification in the means employed for the purpose referred to. Fig. 4 is a detail, the same being an end view, enlarged, of the upper portions of the vise. Fig. 5 is a detail showing another modification of construction, and Fig. 6 is an enlarged representation showing one end of the vise, viewed from the front, when constructed as shown in Figs. 1, 2, and 4.

Like letters of reference indicate like parts.

A A' represent vertically-arranged arms, upon the upper ends of which are horizontal extensions a a', constituting the jaws of the vise. These arms are united at their lower ends, but the jaws thereon are free or somewhat apart from each other, as shown. The

arm A is the inner or fixed arm and is provided with ears or lugs b b to admit of the vise being attached with facility and firmness to a bench or table. On the inner side or face 55 of the outer arm, A', is a stud or horizontal extension, c, recessed or cut out at its end to receive a pad or presser, d, made of rubber, leather, or other comparatively soft material, the purpose of which is, by bearing against 60 the saw when the latter is confined in a vise, to prevent or diminish the vibration of the saw while it is being filed, and thereby prevent or diminish the noise which might otherwise then be made. In practice I prefer to make 65 all of the parts now referred to, excepting, of course, the pad d, in one and the same piece of cast metal, having sufficient flexibility, when made in the form shown, to permit the outer jaw to be compressed against the saw, 70 and when released to spring sufficiently away from the saw to release it. Ordinary cast-iron will admit of this movement.

B B are studs or posts projecting vertically from the jaw a and arranged at or near its 75 ends, and B' B' are oppositely-arranged studs or posts on the jaw a'. These studs or posts may be cast in one and the same part or piece with those parts of the vise already described.

C C are arms or bars pivoted to the posts 80 B B, and D D are levers having eccentric heads or ends e e and pivoted to the outer or free ends of the arms C C. It will be perceived, particularly on reference to Figs. 2 and 4, that the levers D D, when lowered, 85 will cause their eccentrics e e to bear against the outer jaw and force it to a greater or less extent, according to the position of the said levers, toward the inner jaw, so that a saw placed between the jaws will be firmly grasped 90 and held for being filed. It will also be perceived that the saw may be readily released by raising the said levers, and that the vise is well adapted to saws varying from each other in thickness.

Having now shown and described the features of my invention and the means which I deem best for reducing it to practice, I desire to state that I do not here intend to restrict myself particularly to all of the details of 100 construction so far referred to, for the construction may be somewhat varied, or even

some parts omitted, without a material departure from the principle of my invention. For example, the posts B B', instead of being vertical, as shown in Figs. 1, 2, and 4, may be horizontal, as shown in Fig. 3, and a thumb-screw, *f*, as shown in Fig. 5, may be employed instead of the eccentric-levers D D with like results, although, as before stated, I prefer to employ the eccentrics. Again, it is not absolutely essential, though preferable, to apply an auxiliary presser on the free ends of the arms C C, for those arms, as shown in Fig. 3, may be so formed as to perform the function of an eccentric, being curved, as there shown, to bear with greater or less force, according to their position, against either the outer jaw of the vise or against a pin, *f'*, extending from the ends thereof.

Having thus described my invention, what I claim as new, and desire to secure by Letters Patent, is—

1. The saw-vise jaws A A' a a', having thereon the recessed stud or extension *c*, arranged for holding a pad against the saw, all

made in one and the same piece, substantially 25 as and for the purposes specified.

2. The saw-vise jaws A A' a a', having thereon the extensions B B', all made in one and the same piece, in combination with the pivoted arms C C, provided at their free ends 30 with movable or adjustable jaw-compressors, substantially as and for the purposes specified.

3. A saw vise or clamp in which the jaws and their supporting-arms are made in one and the same piece of cast metal, sufficiently 35 flexible to permit the jaws to be clamped upon and released from the saw, and in which the said single or unitary part is combined with one or more clamps for temporarily clamping the saw between the jaws, substantially as 40 and for the purposes specified.

Signed at Waterloo, in the county of Seneca and State of New York, this 3d day of July, A. D. 1888.

ROBERT F. DARLING.
